UNITED STATES PATENT OFFICE.

LOUIS BERZON, OF PHILADELPHIA, PENNSYLVANIA, ASSIGNOR OF ONE-THIRD TO HIMSELF, ONE-THIRD TO JOSEPH BREZIN, AND ONE-THIRD TO WILLIAM KOSAKOFF, ALL OF PHILADELPHIA, PENNSYLVANIA.

SPOOLING MACHINE.

Application filed July 28, 1922. Serial No. 578,036.

To all whom it may concern:

Be it known that I, LOUIS BERZON, a citizen of the United States, residing at Philadelphia, county of Philadelphia, and 5 State of Pennsylvania, have invented a new and useful Improvement in Spooling Machines, of which the following is a full, clear, and exact description, reference being had to the accompanying drawings, which 10 form a part of this specification.

My invention relates to yarn winding apparatus, wherein the yarn is drawn from a certain source and wound upon spools or bobbins as a step in the textile industry 15 called "spooling."

In machines of this character, it is common to have the spools mounted horizontally, one end resting upon the periphery of driving wheels on a constantly driven shaft, 20 by which the spools are frictionally rotated. The yarn, which may be a very fine thread of silk, is uniformly fed over the surface of the spool by means of a guide which is constantly reciprocated back and forth before 25 the spool.

When the spool is thus filled, it is necessary to break the thread and replace the 30 filled spool with an empty one. This is done by hand and as each operator has to tend to the winding of hundreds of spools it is impossible for him to stop and change each one at the right time. The result is that spools 35 delivered contain varying amounts of yarn on them, besides requiring great watchfulness and more operators to do the work.

The object of my invention is to automatically stop the spools when they have 40 been wound with a certain amount, thus visually calling the attention of the operator to their being full and giving him time to replace and start them again. My automatic stop raises the end of a filled spool out of contact with its driving wheel. Thus, with my invention, the operator has a 45 definite stop to go by. A glance at a machine shows him when spools are cocked up out of line and stopped, and he is able to tend many more spools than before, besides delivering each one of them filled to the 50 same predetermined amount.

I will now describe my invention in detail, an embodiment of which is shown in the accompanying drawings, in which—

Fig. 1 is a front view of a portion of a spooling machine with my invention applied thereto. 55

Fig. 2 is an end view of same shown by a section on line 2—2 Fig. 1.

Fig. 3 is a perspective view of the stop mechanism spread apart for clearness. 60

Fig. 4 is an end view of same looking from the left at Fig. 3.

Figs. 5 and 6 are corresponding vertical sections showing the latch in set and tripped positions. 65

Fig. 7 shows various other forms of latch.

As shown in Figs. 1 and 2, the winding machine comprises a longitudinal pipe frame *a* to which are attached cross frames *b*, only one of which is shown. The cross frame projects in two similar arms *c* on either side of frame *a*, which arms carry sockets at their ends for spools *d*. These sockets are double, one portion *e* having a bottom and supporting one end of the spool spindle, the other portion *f* having no bottom (as clearly shown in Fig. 2), wherein the opposite end of the spool spindle floats. This end of the spindle has a weighted drum portion *g* which rests upon a wheel *h* carried by driving shaft *i*. 75

Each socket *e*—*f* is, therefore, arranged to carry the supported end of one spool and the floating end of the spool next to it, and each spool is rotated by its heavy portion *g* resting upon a driving wheel *h*. 85

The yarn *y* is taken from the hank or other source and fed uniformly across the face of the spool by passing through an eye *j* on longitudinal bar *k* which is reciprocated back and forth by means not shown as it is well known in the art and does not enter into the scope of my invention. 90

For my automatic stop I provide a bracket *m* secured to the machine as by saddle and screw *l*. Pivoted to the under part of this bracket is a lever *n*, carrying at its rear end a weight *o* and at its forward end a hinged upright *p*, which has pin and slot connection with the bracket at *q*. Lever *n* is ar- 100

ranged to extend directly beneath the driven end head of spool *d*, so that, when free to act, weight *o* will cause the forward end of the lever to raise this end of the spool away from its driving wheel *h*.

To hold lever *n* out of action, I provide a latch *r* pivoted to a flap *s* hanging from a hinge pin at the top of bracket *m*, see particularly Figures 5 and 6. When lever *n* is 10 down out of action, the upright *p* is held down by latch *r*, as shown in Fig. 5. A depending piece *t*, suspended from the same hinge pin as flap *s*, hangs in such position that it rests against the upper part of latch 15 *r* and is sufficient to prevent the latch from turning.

The lower end of piece *t* carries an adjustable point *u*, between the feeding frame *h* and the spool. Thus as the spool fills up and 20 the line of the yarn from eye *j* rises higher, layer by layer, until the spool is considered full, point *n* is set to come in the path of the yarn, and being curved or bevelled towards the latch, in the next movement of the 25 feed away therefrom, the yarn will catch said point and move it enough to take the pressure of piece *t* off of the latch. This allows the latch to turn on its pivot and upright *p* instantly slips past, into position shown in 30 Figure 6. In this movement, lever *n* acts and raises the spool above it out of action as described, shown in broken lines in Figure 4. After breaking the yarn and replacing the 35 filled spool with an empty one, the operator has only to depress the end of lever *n* with his finger, when upright *p* again latches itself, and the device is ready for another operation.

Point *u* is adjustable by means of set 40 screw *v* to act when any desired amount of yarn has been wound. I have described the mechanism for one spool, but it is understood that there is similar mechanism for each spool; and if points *u* are all set for the 45 same rise the wound spools will all contain approximately the same amount of yarn.

The form of latch *r* may be varied and 50 Figure 7 shows other forms that may be used in place of the hammer-shaped piece shown in the other figures. The hammer head acts as a stop for the upward movement and where no such head exists pin and slot *q* will act as a stop.

Having now fully described my invention, what I claim and desire to protect by Letters Patent is:

1. In a yarn spooling machine, a spool, means to drive the spool, a thread of yarn to be spooled, means to reciprocate the thread of yarn in its passage to the spool longitudinally thereof during the winding operation, and means actuated by the reciprocated thread of yarn in its passage to the spool adapted to interrupt the drive of the spool. 65

2. In a spooling machine, in combination, a spool, a friction wheel adapted to drive the spool, a lever adapted to act to lift said spool out of driving relation with the friction wheel, a latch adapted to normally hold 70 said lever out of action, and means acting, when said spool is full, to trip said latch and permit said lever to act to lift said spool.

3. In a spooling machine, in combination, a spool, a friction wheel adapted to drive 75 the spool, a lever adapted to act to lift said spool out of driving relation with the friction wheel, a latch adapted to normally hold said lever out of action, a trip for said latch adapted to be actuated by contact with the 80 thread of yarn passing to the spool when the spool is filled to the required amount.

4. In a yarn spooling machine, a driving wheel, a spool driven by said wheel, a reciprocating yarn feed, yarn passing from the 85 feed to the spool, a lever for lifting the spool out of driving relation with the wheel, a latch to hold said lever inactive, and a point for tripping the latch, said point being actuated by the yarn itself in the reciprocation which lays the last layer it is desired to 90 wind on a spool.

5. A stop for a yarn spooler comprising, in combination, a spool, yarn being fed to the spool, a reciprocating feed for the yarn, 95 a wheel adapted to drive the spool, an arm for lifting the spool out of driving relation to the wheel, a latch to restrain said arm, a trip for springing the latch, and means to adjust the trip to act when a predetermined 100 amount of yarn is wound on the spool.

In testimony of which invention, I have hereunto set my hand, at Philadelphia, Pa., on this 26th day of July, 1922.

LOUIS BERZON.
